UNITED STATES PATENT OFFICE

JOSEPH HOURIGAN, OF NEW KENSINGTON, PENNSYLVANIA, ASSIGNOR TO ALUMINUM COMPANY OF AMERICA, OF PITTSBURGH, PENNSYLVANIA, A CORPORATION OF PENNSYLVANIA

CORE REMOVING DEVICE

Application filed October 31, 1929. Serial No. 403,704.

This invention relates to the removal of cores from castings of metal and is particularly concerned with the removal of non-collapsible cores from castings of relatively large dimensions. Frequently the metal cast around the core adheres to the core so tightly that the core cannot be readily withdrawn without application of considerable force. To apply that force it has been customary to use presses, punches, hammers, or the like, by means of which the force is exerted on either the casting or the core, or on both, in such manner as to press out or withdraw the core from the casting cavity. In cooperation with such force exerting means there has also been employed cooling devices designed to cool the hot core and cause it to draw away from the metal surrounding it.

Although the above core removing schemes have been found operable, they are very slow in operation and consequently are impractical where a large number of castings or ingots are being made. Moreover, such apparatus is bulky, and expensive both in initial construction and in upkeep, and requires during operation considerable expert supervision because of the great stresses exerted in the ingot, which sometimes crack the ingot or injure its workable properties.

It is an object of this invention to provide a method of removing cores from castings which is automatic in action and comprises a quick, single and continuous operation caused without the exertion of such excessive force as will produce serious strains or other faults in the casting. It is a further object of the invention to provide means for accomplishing core removal which are relatively inexpensive in construction and operation and readily operable by unskilled persons.

Further and other objects and advantages will be apparent from the specification and claims, and from the drawings which by way of illustration show what is now considered the preferred embodiment of the invention.

Fig. 1 illustrates a top plan view of a circular billet mold having a non-collapsible core centrally located therein.

Fig. 2 is a vertical sectional view on the line 2—2 of Fig. 1.

Fig. 3 is a vertical sectional view of the cast billet and the core after removal of outer mold, in operative position on the core-extruding mechanism, which is also in cross-section.

Fig. 4 is a sectional view on the line 4—4 of Fig. 3.

Fig. 5 is similar to Fig. 3 but illustrates a modification of the apparatus shown in Fig. 3.

Fig. 6 is a cross-section on the line 6—6 of Fig. 5.

In the drawings, 10 represents a mold consisting of two parts, made of iron or other suitable material, interconnected by a hinge 12 and adapted to be held closed by the mold latch 14. The mold is mounted upon a suitable base plate 16. In mold 10 when in the closed position is axially disposed, by means of the aligned cavity 18 in the block 16 and the centering lugs 20 which are attached to the hinged mold sections, a hollow core 22 which is closed at its upper end by means of the welded cap 24 into which may be threaded an eye bolt 26. The hollow core 22 is provided at its lower end with a cylindrical opening, the inner edge of which is beveled as shown at 28.

The mold, core, and base plate are assembled as illustrated in Figs. 1 and 2 and into the mold cavity so formed there is cast the metal which on solidification forms the ingot 30. After solidification has been completed, the hinged sections of the mold are swung apart by a manipulation of the latch 14 and the ingot and core are withdrawn by any suitable device, such as the cable 32, which may be attached to the eye bolt 26.

The core, with the ingot tightly adhering thereto, is then transferred to the core-removing mechanism, which in this embodiment of the invention consists of a conical sealing block 34 supported on a base plate 36. A central bore is provided in 34 through which extends a pipe 38 connected through the wall of the block 34 to a main supply pipe 40 controlled by a quick acting valve 42. A drain pipe 44, controlled by the valve

46, also communicates with the central bore. The core, which with its surrounding ingot is still at a high temperature, is seated upon the conical block with the beveled edge 28 5 of the core opening resting on the conical surface of the sealing block, thus forming, because of the weight of the core and ingot, a more or less perfect seal.

In operating the apparatus, the operator 10 by means of the quick acting valve 42 allows a high pressure stream of water, or other fluid cooling means, to issue from the pipe 38 and impinge on the hot walls of the core cavity. The cooling action of the water on the core walls acts to contract the core and 15 to draw it somewhat away from the ingot. Simultaneously there is generated, because of the high temperature of the core walls, a considerable amount of steam which quickly builds up a pressure in the core cavity sufficient to lift the combined weight of the core 20 and ingot upwardly and away from the sealing block, the degree of pressure exerted by the generated steam being controlled by a 25 predetermined setting of the valve 46 in the drain pipe 44. The upward movement of the core and ingot away from the sealing block breaks the seal which is formed on the walls of the sealing block by the beveled edge 30 28, thereby exhausting the steam which has accumulated in the core cavity and by dissipating the pressure built up therein causing the core and ingot to fall with a sudden jar back into the original position. The further 35 action of the water on the core cavity will again generate sufficient steam pressure to remove the core and billet assembly from the sealing block so that the core and the billet are caused to alternately rise and fall 40 with a pounding action which is of sufficient force to drive the billet free from the core. Throughout the operation the core is positively connected to an aligning means such as the hoist cable 32 and the quantity of water 45 is preferably closely controlled by the quick acting valve 42.

When water is used as the cooling and pressure generating means the upper end of delivery pipe 38 is advantageously provided 50 with a cap 48 which will atomize the liquid and distribute it evenly over the inner walls of the core. However, the cooling and pressure generating means may be a gas in which case such an atomizing device would be unnecessary. The main desideratum is that the cooling and pressure generating means, be it a gas, liquid, or similar fluid substance, should be quickly and more or less evenly distributed in rapid contact with the core 55 walls. To accomplish this there may be utilized a foot valve by which the operator may shut off and reopen the delivery pipe as the ingot and core assembly rises and falls or automatic means may be used such as, for 60 65 instance, the automatic valve shown in Fig.

5, which comprises a valve 50, operated by an arm 52. To the arm 52 is attached a rod 54 which is slidably engaged by the guides 56 attached to the inner wall of the sealing block 34. The upper end of rod 54 culminates 70 preferably in a knob 58 which is engaged by a stop 60, shown in the form of a perforated annulus welded to the interior of the core shell 22, and so positioned as to exert a downward force on the rod 54 when the core is seated on the sealing block 34 thus opening the valve 50 and closing it only when the core has been raised from the sealing block as above described. A spring 62, surrounding rod 54 between knob 58 and guide 56, 80 serves to close valve 50 when rod 54 rises.

It is to be understood that the invention is not limited to the specific embodiment herein illustrated and described but may be used in other ways without departure from 85 its spirit as defined by the following claims.

I claim—

1. In apparatus of the class described, in combination, a hollow core adapted to have a billet of metal cast therearound, means for 90 cooling the interior of said core whereby it tends to shrink away from the billet, and means for simultaneously hammering said core to separate said core from said billet.

2. In apparatus of the class described, in 95 combination, a hollow core adapted to have a billet of metal cast therearound, means for spraying water on the inner walls of said core whereby said core is cooled and tends to shrink away from the billet, and means for 100 simultaneously hammering said core to separate said core from said billet.

3. In apparatus of the class described, in combination, a hollow core adapted to have a billet of metal cast therearound, means for 105 spraying water on the inner walls of said core whereby the heat of said core turns the water into steam, and means operable by said steam for driving said core from said billet.

4. The invention set forth in claim 3, in 110 which means is provided for regulating the pressure of said steam.

5. In apparatus of the class described, in combination, a hollow core adapted to have a billet of metal cast therearound, means for 115 spraying water on the inner walls of said core whereby the heat of said core turns the water into steam, and a support for said core and billet, said steam being effective to raise said core and billet from said support, for the purpose set forth.

6. In apparatus of the class described, in combination, a hollow core adapted to have a billet of metal cast therearound, means for spraying water on the inner walls of said 125 core whereby the heat of said core turns the water into steam, a support for said core and billet, said steam being effective to raise said core and billet from said support, and means effective when said core is raised from said 130

support for exhausting said steam from said core interior whereby said core is caused to drop back onto said support.

7. In apparatus of the class described, in combination, an annular core having open and closed ends and adapted to have a billet of metal cast around the cylindrical sides thereof, a conical block adapted to enter the open end of said core to seal said opening and support said core and billet, means for spraying water through said support into the interior of said core whereby the heat of said core converts the water into steam which raises said core out of contact with said support to exhaust the steam between said core and said support whereby said core drops back onto said support, for the purpose set forth.

8. The invention set forth in claim 7, in which automatic control means is provided for admitting additional water when said core drops back onto the support and for shutting off the water when the core is raised from the support.

9. In the method of removing a hot hollow core from a hot billet surrounding said core, the steps of cooling the interior of said core by a cooling medium sprayed thereinto, and simultaneously hammering said core whereby said core is driven out of said billet.

In testimony whereof I hereto affix my signature.

JOSEPH HOURIGAN.
